[57] ABSTRACT

A monitoring and alarm system including a plurality of sensors located at various remote stations, each sensor being provided with a detector switch which is normally closed and which opens when any abnormal condition, such as fire or smoke is sensed. Each detector is connected by a two-wire line to a respective pair of terminals at a central console, across which is shunted an indicator lamp in series with a diode. The terminal pairs are connected in a series chain to a direct-current source, such that when all of the associated detector switches are closed, the chain is unbroken and the lamps are short circuited out of the chain, but when any detector is caused to open, the lamp associated therewith is then interposed in the chain and is energized through a flasher circuit to produce a pulsatory indication identifying the station responsible therefor.

FIRE AND SMOKE MONITORING AND ALARM SYSTEM

RELATED APPLICATION

This application is related to my copending application Ser. No. 818,677 filed Apr. 23, 1969 on a "Monitoring System for Door Stations."

BACKGROUND OF INVENTION

This invention relates generally to monitoring and alarm systems, and in particular to a system in which the existence of fire, smoke or any other abnormal condition is sensed at any station in a multiple-station installation to produce a switching action functioning to identify the responsible station at a central console where an alarm is also given.

In one known form of fire alarm system, detector heads are placed at various stations throughout a structure, the heads all being linked by lines to a common alarm circuit. The heads, which are usually constituted by bimetallic switches or equivalent elements are temperature sensitive and operate in response to an abnormal rise in temperature to actuate the alarm circuit.

While in a system of this type, the alarm calls attention to a hazardous condition somewhere in the structure, it does not actually identify the activated detector and hence does not point to the location of the fire. This is a serious drawback when the installation is made in a multiple-story building, a large warehouse or in any other elaborate structure, for precious time may be lost in finding the cause of the alarm.

To overcome these drawbacks, systems have been proposed in which each station detector is coupled to an indicator on a central annunciator board which identifies the activated detector. In such systems, when a given detector switch is closed, current flows through the line extending from the switch to the associated annunciator relay to actuate the relay. The difficulty with this arrangement is that where the detector lines are distributed among various stations throughout a large building or other installation, the length of the lines may introduce substantial resistance in the circuit. Consequently the voltage established at the annunciator board may fall below the value necessary to actuate the associated indicator relay.

While it is possible to compensate for the effect of line resistance, the resultant arrangement becomes relatively complicated and costly. Moreover, in some situations, particularly where the lines go through an environment which may contain explosive gases or chemicals, the current-carrying lines themselves constitute a possible hazard, for the current therethrough is relatively heavy and might produce sparking at the detector contacts or elsewhere in the line should there be a failure in line insulation.

BRIEF DESCRIPTION OF INVENTION

Accordingly, it is the main object of this invention to provide an improved alarm system in which a plurality of sensors at various remote stations are coupled by individual lines to lights or other indicators on a central console so that the existence of an abnormal condition at any station is indicated at the console and an alarm given.

More specifically, it is an object of this invention to provide a system of the above type, in which the status of each station is indicated by means of individual light indicators, a single relay and alarm device common to all stations, whereby the sounding of the alarm alerts a supervisor who then, by viewing the indicators, can identify the responsible station or stations.

Also an object of the invention is to provide an alarm system of simple, reliable and efficient design, which may be manufactured at low cost and wherein the lines extending from the central console to the stations operate at very low current and voltage levels and offer no danger to building personnel. Nor do these lines constitute a fire hazard.

The invention has many practical applications, for the detectors at the various stations may be made sensitive to fire, smoke, gas or any other abnormal condition, or in the alterna-

tive, the detectors may be made responsive to an unauthorized entry, such as at a window or door.

Briefly stated, these objects are accomplished in an alarm system in which a plurality of sensors located at remote stations each includes a normally open detector switch which closes only when an abnormal condition, such as fire, arises. Each detector switch is connected by an extended two-wire line to a respective pair of terminals at a central console.

Across each pair of terminals is shunted a lamp in series with a diode. The terminal pairs are connected in a series chain to a voltage source whereby when all associated detector switches are closed, all lamps are bypassed thereby and the chain is unbroken, but when any detector switch is open, the lamp associated therewith is then interposed in the chain and is energized through a flasher unit to produce a pulsating light indication identifying the station responsible therefor. The arrangement is such that when a lamp is energized, an alarm is also activated to alert a supervisor at the console location.

BRIEF DESCRIPTION OF DRAWING

For a better understanding of the invention, as well as other objects and further features thereof, reference is made to the following detailed description to be read in conjunction with the accompanying drawing, wherein:

FIG. 1 is a perspective front view of the console included in an alarm system in accordance with the invention;

FIG. 2 shows the console from the rear and the line connections therefrom to detectors at remote stations; and

FIG. 3 is a schematic circuit diagram of the system.

DESCRIPTION OF INVENTION

Referring now to FIGS. 1 and 2, in an alarm system in accordance with the invention, a central console 10 is installed in a control booth or at any other supervisory position, a bank of lamps L-1 to L-10 being mounted on the front panel thereof. Each lamp represents a respective remote station (I to X), and serves to indicate the status of its associated station. It is to be understood that while ten lamps are shown, in practice the system may include a smaller or larger number of stations and a corresponding number of indicators at the console.

A row of 10 terminal pairs T-1 to T-10 is mounted on the rear of the console, each pair corresponding to a lamp and being connected by a two-wire line (L₁ to L₁₀) to sensors D₁ to D₁₀, respectively, at remote stations I to X, placed at various points throughout the building or wherever else the installation is made. Thus in a motel having 10 units, a sensor may be placed in each unit, the console being installed in the office. The length of the line wires is not a factor in the operation of the system, and light-gauge wire may be used.

Each sensor (D₁ to D₁₀) includes a normally open detector switch which is caused to open in response to an abnormal condition. Thus in the case of a fire alarm system, the switches may be operated by bimetallic elements adjusted to cause the associated switch to open only when the temperature at the station rises above a preset level.

In practice, the fire detectors may be associated with a sprinkler system. In a sprinkler system, a sprinkler head coupled to a waterline is provided with a thermally sensitive fusible valve lock which melts when the ambient temperature rises above a safe level, thereby releasing the flow of water to extinguish the fire. By the time this happens, the fire may be fairly well advanced, and the release of the sprinkler may cause water damage.

By clipping or otherwise linking a detector switch to a sprinkler head and setting the detector so that its switch closes at an abnormal temperature level, which is nevertheless somewhat below the level at which the sprinkler lock melts, the supervisor at the control console may be alerted to a dangerous condition at a particular station and be in a position to take steps to correct this condition before the sprinklers are activated.

The detectors at the various stations may be made sensitive to any other condition, such as gas, noise, moisture, or whatever other factor is to be monitored. The system can also be made to operate as a burglar alarm by so arranging the detector switches at points of entry in a building that the switch is caused to open only when an unauthorized entry is made, the associated lamp at the console identifying this point.

Mounted within the console, is an alarm such as buzzer BZ, which is activated when any one of the lamps is caused to operate. The alarm serves to alert the supervisor, so that by locking at the lamp bank on the panel, he will be advised of which station is responsible for the alert.

Referring now to FIG. 3, the electrical circuit of the system is shown, power therefor being supplied by a power supply including a stepdown transformer 11, whose primary 11A is connected through a master switch 12 to the AC powerline. The secondary 11B of the transformer is connected to a full-wave rectifier network provided with diode rectifiers 13 and 14 to produce a DC output (12 volts) at output terminals DC+ and DC-. Alternatively, the necessary power for operating the system may be provided by batteries.

A single relay RL is provided for operating all of lamps L-1 to L-10. The relay includes a solenoid 15 which, when energized, simultaneously actuates four ganged switch sections S₁, S₂, S₃, and S₄, each of which has an armature M, an upper fixed contact A, and a lower fixed contact B. In the deenergized state of the relay, the armatures M all engage their associated upper contacts A, the armatures being pulled over the lower contacts B only when solenoid 15 is energized.

Each pair of terminals (T-1 to T-10) is connected by its related line (L₁ to L₁₀) to a respective detector switch (D₁ to D₁₀) at a remote station, (I TO X), but in the event less than the total number of available terminals is in use, the unused terminal pairs are each shunted by a jumper, such as jumper 16, across terminal pair T10. The terminal pairs are connected in series between points X and Y to form a series chain, and when all terminal pairs are shunted by closed detector switches or jumpers, the series chain is unbroken to provide a conductive path which extends through all of the associated lines L₁, L₂, etc.

Each lamp is connected in series with a respective diode LD1, LD2, etc., across the correspondingly numbered terminal pair T-1, T-2, etc., and since each detector switch D₁, D₂, etc., associated with the terminal pair is normally closed, the series lamp circuit thereacross is effectively bypassed in the series chain. Point X in the series chain is connected to armature M of switch section S₃, while point Y is connected to armature M of switch section S₄.

A flasher unit is provided to operate the lamps intermittently (i.e., one-half second on, one-half second off). This unit comprises a flasher relay RF whose solenoid 17 is connected to a unijunction solid-state relaxation oscillator constituted by transistors 18 and 19, resistors 20, 21, 22, and a capacitor 23. The RC time constant of the circuit is such as to energize solenoid 17 at the desired flashing rate.

Solenoid 17 of the flasher relay actuates a single switch section S₅ having an armature M, an upper fixed contact A, and a lower fixed contact B, the armature normally engaging contact A. One end of the relaxation circuit is connected through conductor 24 to the negative terminal DC- of the voltage source, while the other end is connected through conductor 25 to armature M of switch section S₅ whose A contact is connected to the A contact of switch section S₃ of the lamp relay RL.

Buzzer BZ is AC operated and is connected across one-half of transformer secondary 11B through armature M and contact A of switch section S₂. Hence, at the outset, when relay RL is deenergized, the AC buzzer circuit is completed and the buzzer sounds. A pilot light 26, located on the front panel of console 10, is connected directly across the same one-half of secondary 11B; hence when master switch 12 is closed, the pilot light is energized to indicate that the console is operative.

A reset switch button 27 is connected between positive supply terminal DC+ and through diode 28 to the upper end of solenoid 15 of relay RL the lower end of which is permanently connected to the negative supply terminal DC-.

5 Thus when reset button 27 is momentarily depressed, the DC output of the supply is applied across the solenoid and relay RL is momentarily energized, by the full output of the DC power supply, causing armatures M of switch sections S₁ to S₄ to engage their respective B contacts. Since the buzzer circuit 10 is connected to its AC source through contact A of switch section S₂, the energization of relay RL breaks the buzzer circuit and silences the buzzer.

Momentary energization of relay RL completes a holding circuit therefor, this circuit being constituted by contact B and armature M of switch section S₄, which connects the upper end of solenoid 15 to point Y of the series chain, point X of the chain being then connected through armature M and contact B of switch section S₃ to the positive terminal DC+.

15 It is important to note that lamp relay RL is initially energized by DC voltage passing through reset button 27 and derived directly from the supply in the console, but when the holding circuit takes over to maintain the relay in the energized state, current through solenoid 15 is then by way of the series chain at points X and Y and hence is by way of all of the external lines L₁, L₂, etc., associated therewith.

20 The fact that these external lines may be very long and thereby serve to introduce a significant amount of resistance in the holding circuit, does not mean that relay RL will not be held. The reason for this is that it takes a significantly lower voltage to hold in a relay, once energized, than to effect the initial actuation thereof, for in the latter case, the inertia inherent in the relay must be overcome, and once overcome less voltage is necessary. For example, while it takes 12 volts to initially actuate the relay, it may take as little as 4 or 5 volts to maintain actuation thereof.

25 Consequently, in the holding state, current flows through solenoid 15 of relay RL and through all closed detector switches D₁, D₂, etc., (or equivalent jumpers), by way of the extended lines L₁, L₂, etc. The level of current flow through these lines is very low and is not, therefore, hazardous in any way.

30 When, as a result of a fire at any one of the stations or any other significant change in status which affects the sensor at that station, the associated detector switch is caused to open and the series chain between points X and Y is broken. When this happens, the lamp and diode combination related to the open detector switch is then interposed in the chain.

35 For example, if detector switch D₁ opens, then lamp L-1 and diode LD-1 in series therewith are interposed in the series chain between points X and Y, thereby substantially increasing the resistance offered by the series chain and causing the voltage applied to solenoid 15 of relay RL to fall below the holding level.

40 55 When this occurs, relay RL is deenergized, in which event the flasher unit conductors 24 and 25 are then connected across the DC output at terminals DC- and DC+, for conductor 24 is permanently connected to negative terminal DC-, whereas conductor 25 is now connected by contact A and armature M of switch section S₅ to positive terminal DC+. When the flasher unit is energized, switch section S₅ then proceeds to open and close periodically.

45 60 Switch section S₅, which opens and closes periodically, acts to apply the battery voltage from terminals DC+ and DC- across the series chain at points X and Y which now have lamp L-1 and diode LD-1 interposed therein.

65 70 It will be seen that point Y is connected through armature M and contact A of section S₄ of the deactivated relay RL to positive terminal DC+. It will also be seen that point X is connected through armature M and contact A of section S₃ of relay RL through the armature M and contact A of section S₅ of flasher relay RF, and from there through a current-limiting resistor 29 to the negative terminal DC-. Hence voltage from 75 the DC supply will now flow at a periodic rate determined by

the action of the flasher unit, through lamp L-1, which is interposed in the series chain between points X and Y.

At the same time, since relay RL is deactivated, buzzer BZ sounds an alarm, for it is now energized through armature M and contact A of switch section S₂. Thus the opening of detector switch D₁ at the first remote station I is indicated by the pulsing of lamp L-1, accompanied by the sound of the buzzer.

If another detector switch opens, say detector switch D₆ at station VI, when detector switch D₁ is already open, lamps L-1 and L-6 will then both be illuminated, but in this instance the operating current flowing through the chain between points X and Y is shared by these lamps, hence the lights will be somewhat dimmer.

In order to test the system to see whether it is functioning properly, a normally closed test switch 30 is provided between contact B of switch section S₄ and the upper end of solenoid 15 of relay RL, such that when the relay RL is held by the holding circuit including this switch section, the holding circuit may be broken by opening test switch 30 to be sure that the relay will then drop out.

Because the system can tolerate resistance in the holding circuit, the lines L₁, L₂ etc., may be of light-gauge wire, for the current carried thereby is of very low level and need not be heavily insulated.

While there has been shown and described a preferred embodiment of an alarm system in accordance with the invention, it will be appreciated that many changes and modifications may be made therein without, however, departing from the essential spirit of the invention.

What I claim is:

1. A monitoring system comprising:

- A. a plurality of sensors located at various remote stations, each sensor including a normally closed switch and sensing means to cause said switch to open when an abnormal condition is detected, and
- B. a console at a central supervisory location, said console including:
  - a. a bank of terminal pairs equal in number to said sensors,
  - b. a two-wire line linking each station switch to a corresponding terminal pair,
  - c. a like bank of voltage-responsive indicators, each having a substantial resistance and being connected across a corresponding terminal pair,
  - d. a voltage source for said indicators, said source providing a predetermined voltage,
  - e. a relay having a solenoid, for operating all of said voltage-responsive indicators, said relay having four ganged switch sections including normally open hold-

5

6

ing-circuit contacts and normally closed switching contacts, said relay having an inherent inertia and requiring said predetermined voltage initially to actuate said relay, which predetermined voltage is sufficient to overcome said inertia and is substantially higher than the holding voltage thereafter necessary to hold the relay in the actuated state,

f. switching means connecting said source directly to said solenoid to apply said predetermined voltage thereto to actuate said relay momentarily and thereby to open said switching contacts and to close said holding circuit contacts,

g. means connecting said terminal pairs in a series chain to said voltage source through said holding-circuit contacts whereby said indicators are bypassed when the associated station switches are closed to produce a holding voltage holding said relay in the actuated state, said indicators being interposed in said chain when said switches are open, whereby when a given switch is open the corresponding indicator is activated to identify the responsible station, said activated indicator introducing said substantial resistance in said series chain, which resistance has a value reducing the voltage applied by said holding circuit to a point below said holding voltage and thereby effecting deenergization of said relay whereby said relay switching contacts are caused to close, and

h. means to apply a voltage derived from said source through said closed switching contacts to said chain to operate the activated indicator.

2. A system as set forth in claim 1, further including an alarm device, and means to activate said device when any one of said indicators is activated.

3. A system as set forth in claim 1, wherein said sensors are thermally responsive elements sensitive to fire.

4. A system as set forth in claim 3, wherein said elements are attached to sprinkler heads also having thermal elements, the thermal elements of the sensors being activated at a lower temperature than those of said sprinkler heads.

5. A system as set forth in claim 1, wherein said indicators are each formed by a lamp in series with a diode.

6. A system as set forth in claim 1, further including a flasher unit to provide a pulsatory indication, and constituted by an auxiliary relay adapted to make and break a switch interposed between the chain and the source, said auxiliary relay being energized periodically by a relaxation circuit connected to said source, said flasher unit being activated when said switching contacts of said relay are closed.
